Patented Feb. 19, 1924.

UNITED STATES PATENT OFFICE.

VICTOR S. ALLIEN, OF WILMINGTON, DELAWARE, ASSIGNOR TO DARCO CORPORATION,
OF WILMINGTON, DELAWARE, A CORPORATION OF DELAWARE.

CLEANING SOLVENT.

Application filed January 19, 1922. Serial No. 530,453.

No Drawing.

To all whom it may concern:

Be it known that I, VICTOR S. ALLIEN, a citizen of the United States, residing at Wilmington, in the county of New Castle 5 and State of Delaware, have invented certain new and useful Improvements in Cleaning Solvents, of which the following is a specification.

This invention relates to cleaning solvents; 10 and it comprises a method of purifying solvents (gasoline, benzol, etc.) used in dry cleaning garments, and for similar purposes, wherein such solvent is exposed to centrifugal action in the presence of activated 15 carbon, advantageously that of the Mumford Patent No. 1,286,187; all as more fully hereinafter set forth and as claimed.

In dry cleaning garments, the solvents generally used by the cleaners are gasoline 20 and benzol (coal tar benzene); although occasionally there are used carbon tetrachlorid, chloroform, the chlorethylene; ethylene chlorid, etc., and particularly where non-inflammability is a desideratum. 25 My invention is applicable to any of these solvents in an impure state, but I shall hereinafter more particularly describe it as applied to the treatment of gasoline which may be regarded as typical of the cleaners' 30 solvents. Dry cleaners' gasoline is a special grade of petroleum distillate or of gasoline having a low end boiling point.

While the primary object in using gasoline in dry cleaning is to dissolve and remove grease, gasoline being an excellent solvent for fatty and greasy substances, yet, as a matter of fact, it removes and carries with it dirt of all kinds. After a certain length of time, gasoline used in cleaning 40 becomes too much contaminated or dirty and must be purified. This purification offers considerable difficulty, this being partly because of the wide variety of substances present. In addition to the coarse 45 and easily removed dirt and greases, resins, etc., in solution, there are colloid suspensions or pseudo-solutions of finely divided liquid and solid matters. In cleaning establishments the dirty, used gasoline is ordinarily 50 put in storage tanks to settle out as much dirt as possible and is then frequently run through a centrifugal to separate a further quantity. This, however, is not very effectual and does not give a clean product. A 55 centrifugal does not, of course, remove dis-

solved matters and it takes out but little of the colloidal matter. Distillation is sometimes employed by cleaners in recovering gasoline, but where the gasoline contains free fatty acids (from dissociated soaps), 60 after a few distillations the distillate is apt to become what is known as "sour gasoline", which is not deemed desirable for cleaning and must be discarded.

In the present invention I modify the 65 purification process by incorporating a little decolorizing carbon into the used gasoline prior to the centrifugal separation. While other kinds of activated carbon may be used, I find the type described and claimed 70 in various patents to one Mumford (see No. 1,286,187) best adapted. In treating dirty gasoline, the activated carbon adds several other functions of importance to its 75 ordinary decolorizing function. One of these added functions is removal (to a greater or less extent) of dissolved greases and resins, and another is collection of colloid suspensions and emulsions and their conversion into a form amenable to centrifugal separation. By the simple expedient of adding a little activated carbon to gasoline and agitating the two together for a time, the carbon collects very fine matters in 80 suspension or pseudo-suspension. On then centrifugaling the two are thrown out together. In so doing, a light-colored clean gasoline is obtained suitable for direct use in dry cleaning. If the gasoline treated is 85 acid, that is, contains free fatty acids or resin acids, it is advantageous to use a little calcium carbonate or lime with the carbon, say, one per cent or so, of calcium carbonate on the weight of the carbon. The calcium 90 salts of these fatty and resin acids are insoluble and are collected by the carbon. The gasoline thus neutralized can be distilled without production of "sour gasoline". 95

In a specific embodiment of the present 100 invention, used gasoline is allowed to stand in a storage tank or is filtered in any suitable way to free it of coarse dirt. To this gasoline is then added a small proportion of one of the commercial activated carbons. In the case of the Mumford material, about 35 parts by weight to 100 gallons of used gasoline are advantageous. If the gasoline is particularly dirty, somewhat more may be employed, while if it is fairly 105 clean, the proportion may be somewhat re- 110

duced. With other activated carbons ordinarily considerably more is required. The carbon and the gasoline are well agitated for a period of 10 to 30 minutes and allowed to settle. Much of the carbon deposits, carrying impurities removed from the gasoline with it. Without waiting for a complete separation in this manner, the gasoline is next treated in an efficient separating machine of the centrifugal separator type, thereby removing the residue of the decolorizing carbon, together with dissolved and suspended impurities of the gasolene. Instead of using a centrifugal, a filter press may be employed; but the centrifugal I regard as better. The effluent gasoline is ready for re-use but, if desired, it may be distilled. As the carbon takes out the moisture (of soap emulsions and the like), the gasoline coming from the centrifugal is substantially dry. Where the used gasoline is acid in its nature, it is, as stated, a useful expedient to add a little calcium carbonate at the time of adding the carbon. Or the carbon may be treated with a little lime water prior to use.

What I claim is:—

1. In the purification of used and impure solvents carrying colloidal matter of the type of dry cleaners' gasoline, the process which comprises agitating such a solvent with activated carbon to collect such colloid matter and separating the carbon and collected matter by centrifugal action.
2. In the purification of used and impure solvents carrying colloidal matter of the type of dry cleaners' gasoline, the process which comprises agitating such a solvent with activated carbon in the presence of calcium carbonate to collect such colloid matter and neutralize acidity and separating the carbon and collected matter by centrifugal action.
3. The process of recovering dry cleaners' gasoline, which comprises settling said gasoline to remove coarse impurities, adding activated carbon and calcium carbonate, agitating and separating by centrifugal action.

In testimony whereof, I have hereunto affixed my signature.

VICTOR S. ALLIEN.
